UNITED STATES PATENT OFFICE.

LUDWIG KELTIČKA, OF SCHLES-OSTRAU, CZECHOSLOVAKIA.

PROTECTIVE DEVICE FOR KNEES, ETC.

Application filed March 23, 1923. Serial No. 627,069.

To all whom it may concern:

Be it known that I, LUDWIG KELTIČKA, a citizen of the Republic of Czechoslovakia, residing at Schles-Ostrau, Czechoslovakia, have invented certain new and useful Improvements in Protective Devices for Knees, Etc., of which the following is a specification.

The present invention relates to a protective device for the knee, etc., and consists in a frame for the support of the knee, the said frame being connected with a bottom plate by means of elastic devices in such a manner that the knee when kneeling down rests upon an elastic support.

The object of the invention is diagrammatically represented in the drawings, the elastic devices being composed of springs. Fig. 1 represents a cross view of the protective device, Fig. 2 permits a view in perspective of the device when in use and Fig. 3 represents a view of the device itself.

Underneath a frame 1 consisting of material of greatest elasticity a correspondingly bent flat spring 2 has been provided which is connected with a spiral spring 3. This spiral spring is shaped in such a manner and the coils are arranged in a way that one coil fits into the next lower one when the spring is pressed together. This spring 3 is fitted at its lower free end with a bottom plate 4. The frame 1 is furthermore connected with a spiral spring 5 which is gradually tapering towards the bottom plate and forms a support for a cover 6 preferably consisting of leather, linen, wire nettings or the like surrounding the whole device.

The flat spring 2 on that side turned towards the frame 1 is equipped with an attachment 7 of elastic material, as for instance rubber or the like. The inside of this cap formed by the frame 1 and the spring 2 is also lined with a protective cover 8, made of leather, etc., and between the external cover 6 and the internal cover 8 a stuffing has been provided consisting of horsehair, seaweed or the like.

The bottom plate 4 at its lower side has furthermore been equipped with an additional plate 11 of soft material, as for instance rubber, heel leather, wood, etc., and serves the additional purpose of clamping the cover 6 to the plate 4. As this plate is held by a counter-sunk screw it can easily be interchanged.

The frame 1 is provided with a belt connection 9 which serves to hold this protective device having the shape of a protective cap to the knee, as illustrated in Fig. 2.

This protective device can be used not only for the knee but, in larger sizes, also for the hips, joints, etc., and is especially destined for miners who do most of their work in a kneeling position.

The device may, however, be used for all similar kinds of work, as for instance paving, or at home, and the tapering springs offer the additional advantage that the device can easily be tilted towards all sides.

Having now described my invention and how the same may be performed what I claim and desire to secure by Letters Patent is:

1. A resilient protective device for the knee comprising an outer elastic covering, a support for the knee, a removable bottom plate, and a pair of spiral springs of conical convolutions within said body and between said support and said bottom plate, said springs being telescoped one within the other and each forming substantially a frusto-conical helix.

2. A resilient protective device as embodied in claim 1, and having one of said springs in inverted relation to the other of said springs.

3. A resilient protective device as embodied in claim 1, wherein said springs are so arranged that they occupy a substantially common plane under maximum compression.

In testimony whereof I have affixed my signature.

LUDWIG KELTIČKA.
